STORM WINDOW FRAME

Frederick C. Barrell, Jr., 6100 Pleasant Drive,
Des Moines, Iowa

Filed June 22, 1965, Ser. No. 85,849

Term of patent 14 years

(Cl. D13—1)

FIG. 1

FIG. 2

FIG. 3

FIG. 5

FIG. 4

FIG. 6

FIG. 1 is a perspective view of a storm window frame showing my new design with the panes and the broken line showings of the building and sashes indicated for illustrative purposes only,

FIG. 2 is an elevational view of the side opposite to FIGURE 1,

FIG. 3 is an edge view of one of two like long sides,

FIG. 4 is an edge view of one of two like short sides,

FIG. 5 is a cross sectional view taken on the line 5—5 of FIGURE 1 to more clearly illustrate the design thereof, and

FIG. 6 is a cross sectional view taken on the line 6—6 of FIGURE 1.

I claim:

The ornamental design for a storm window frame, as shown and described.
